US00D967266S

(12) **United States Design Patent** (10) Patent No.: **US D967,266 S**
McMillin et al. (45) Date of Patent: **** Oct. 18, 2022**

(54) **ELECTRONIC DEVICE WITH DISPLAY**

(71) Applicant: **Lyft, Inc.**, San Francisco, CA (US)

(72) Inventors: **Jesse Jones McMillin**, San Francisco, CA (US); **Ethan Duncan Eyler**, San Francisco, CA (US); **Sang Ik Lee**, San Francisco, CA (US); **Christopher Kuh**, San Francisco, CA (US); **Nicholas Robert Barrett**, San Francisco, CA (US); **Sean Patrick Murphy**, San Francisco, CA (US)

(73) Assignee: **Lyft, Inc.**, San Francisco, CA (US)

(**) Term: **15 Years**

(21) Appl. No.: **29/713,840**

(22) Filed: **Nov. 19, 2019**

Related U.S. Application Data

(63) Continuation of application No. 29/584,381, filed on Nov. 14, 2016, now Pat. No. Des. 868,895.

(57) **CLAIM**

The ornamental design for an electronic device with display, as shown and described.

DESCRIPTION

FIG. 1 is a front perspective view of an electronic device with display showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a bottom plan view thereof.

The broken lines within the Figures show portions of the electronic device with display that form no part of the claimed design.
